UNITED STATES PATENT OFFICE.

JOHN MOORE, OF SYRACUSE, NEW YORK.

EXTENSION WINDOW-CORNICE.

SPECIFICATION forming part of Letters Patent No. 240,837, dated May 3, 1881.

Application filed January 26, 1881. (No model.)

To all whom it may concern:

Be it known that I, JOHN MOORE, of Syracuse, Onondaga county, State of New York, have invented a new and useful Improvement 5 in Extension Window-Cornices, of which the following is a specification.

There have been several attempts to form extension-cornices for windows and like purposes, all of which, so far as I am informed, 10 have lacked the elements of entire success.

By my mode of construction I cheaply form a strong and practical cornice, easily adjusted, and of perfect finish, expanding and contracting to any desired degree.

15 The construction of my improvement is described as follows, illustrated by the accompanying drawings, in which—

Figure 1 is a view of the inner side of the cornice; Fig. 2, a cross-section; Fig. 3, perspective view of inside of center-piece detached; Fig. 4, front view of the cornice.

The cornice may be made of any design in molding, as in Fig. 4, the front being divided at its center into two equal parts, *a a*. Upon 25 the back of one of these parts *a* two stout parallel bars, *b b*, are securely affixed, and project over onto the other side an equal distance, the length of said bars determining the extension of the cornice. On the inner edges of the 30 bars *b b* are match-grooves, as distinctly shown in cross-section, Fig. 2. In the space between them a bar, *c*, fits and slides, having tongues on each edge to fit into the grooves in *b b*. This bar *c* is affixed to one of the parts *a*, and

the two parts *a a* are thus securely united, with 35 freedom to be drawn out or contracted. The projecting ends of bars *b b* are firmly united by a brace, *d*, to resist the strain upon them caused by bar *c*, tending to pry them apart.

To cover the center space formed by drawing the side pieces, *a a*, apart, I employ an ornamental center-piece, *e*, of any suitable design, and of sufficient length to lap over and cover the ends of pieces *a a* when the cornice is expanded as far as it is required. The inner face 40 of this center-piece should conform to the molding against which it rests, and at its ends be covered with soft material *ff* to bear against and slide on the molding of the end pieces without chafing it. This center-piece is affixed 45 in place by hooks or turn-buckles, to hold it properly in place and allow it to be readily removed, as seen in section, Figs. 2 and 3.

Having thus fully described my invention, I claim—

1. The combination of the end *a* having the bars *b b* affixed thereto with the end *a* having the bar *c* affixed to it, the bar *c* being jointed to and sliding between the bars *b b*, substantially in the manner and for the purposes 55 specified.

2. The combination of the projecting bars *b* and connecting-brace *d*, as and for the purpose specified.

JOHN MOORE.
